UNITED STATES PATENT OFFICE.

WILLIAM A. RICHARDSON, OF EDWARDSVILLE, ILLINOIS, ASSIGNOR TO RICHWIN MANUFACTURING COMPANY, OF CHICAGO, ILLINOIS, A CORPORATION OF ILLINOIS.

CLAMP.

1,243,106.

Specification of Letters Patent. Patented Oct. 16, 1917.

Application filed December 2, 1916. Serial No. 134,670.

To all whom it may concern:

Be it known that I, WILLIAM A. RICHARDSON, a citizen of the United States, residing at Edwardsville, in the county of Madison and State of Illinois, have invented certain new and useful Improvements in Clamps, of which the following is a specification.

My invention consists of an improvement in clamps for tightly holding a flexible tying device, as a strap, rope or cord, and is designed to provide a double clamping or locking construction, automatically operative, and having means for easy and quick release. Preferred constructions are shown in the accompanying drawings, in which:

Figure 1 is a sectional view of the device in operative position, with the tying cord in place.

Fig. 2 is a face view in elevation, showing the unlocking keyhole.

Fig. 3 is a vertical sectional view on its line III, III, of Fig. 2, with the unlocking key.

Fig. 4 is a partial similar view showing a modification.

Fig. 5 is a view similar to Fig. 2, showing a further modification.

Fig. 6 is a view of the interior construction of Fig. 5, with the cover plate removed.

Fig. 7 is a vertical sectional view indicated by the line VII, VII, of Fig. 5.

The casing 2 which may be circular or of other preferred form, is provided with a closed bottom 3 and a removable top 4. The top is secured in position by rivets 5 which constitute pivotal pins for the mounting of the two oppositely located and acting dogs 6, each of cam-like construction and having gripping edges which are of constantly increasing radius from the pivotal center 5. Their edges are preferably recessed in the form of a V as shown in Fig. 3, providing a gripping groove having at each inner side corrugations or ridges 7 for tight engagement with the cord or rope 8.

A central rib or bearing abutment 9 extends inwardly from back 3 midway of the casing for sufficient length to form a bearing at each side for the cord and openings 10 are provided at opposite sides of the casing for its passage therethrough. Each dog 6 is preferably provided with a spring 11 bearing by one end against the casing and by the other against the dog to insure its initial gripping action against the cord. An

unlocking disk or lever 12 is rotatably mounted on a stud 13 of the central rib 9 and has link connections 14 with each dog whereby when the disk is rotated, the clamping dogs may be positively lifted away from engagement and against the action of springs 11.

Cover 4 is provided with a key hole 15 and a key 16 having wings 17, is adapted to be inserted through the key hole and to engage lugs 18 of disk 12 for unlocking, as will be readily understood.

When the cord 8 is passed through the casing openings 10 and looped as shown, around a mail bag, package, bundle, or any other article to be tightly fastened, casing 2 is forced toward the article, or the free ends of the cord are tightly drawn, the dogs being pressed against the cord by their springs. Then the tension of the loop will exert a reverse strain, and the eccentric faces of the dogs will cause them to bite inwardly toward the cords, tightly pressing them against the central ridge. The gripping effect will increase in proportion to the strain and the cord will thus be positively held until released.

If desired, the gripping dogs 6^a may have straight transverse faces and the central ridge 9^a may be grooved to receive the cords, as in Fig. 4, thus insuring good surface engagement.

Instead of the lock and key construction above described, I may use a sliding block 12^b having a stem extending out through a slot 15^b and provided with a terminal button 16^b for operation by the finger or thumb, as in Figs. 5, 6 and 7. Block 12^b is connected with dogs 6^b by links 14^b and the construction and operation is the same otherwise as above described, the parts being the same and identified by similar numerals having the exponent "b".

With either of the above described constructions, the cord, after having been loosely located in position through the openings 10 of the casing and between the oppositely acting dogs 6 and the intervening bearing ridge, with the tendency of the dogs to normally bind inwardly against the cord, upon tightening the loop as described, the dogs will thereupon grip and hold it until released.

The device provides a very convenient, simple and economical means for effecting a

looped engagement upon or around various articles; it is extremely compact, very efficient, and may be made in a great variety of designs as to the casing, or otherwise changed by the skilled mechanic, to adapt it to its intended functions.

Having described my invention, what I claim is:

1. In a holding device of the class described, a casing provided with clearance openings through its edges, a middle bearing abutment, a pivotally mounted locking dog at each side of and adapted to bind inwardly toward said abutment, and manually operated means for simultaneously retracting said dogs, said means being mounted within the casing, and adapted to be operated from without.
2. In a holding device of the class described, a casing provided with clearance openings through its edges, a middle bearing abutment, a pivotally mounted locking dog at each side of and adapted to bind inwardly toward said abutment, and manually operated means positively connected to each of said dogs for retracting them.
3. In a device of the class described, a base, a centrally spaced bearing abutment thereon, a pivotally mounted spring pressed locking dog at each side of and adapted to bind inwardly toward said abutment, and manually operated means adapted to simultaneously retract said dogs.
4. In a device of the class described, a base, a centrally spaced bearing abutment thereon, pivotally mounted locking dogs adjacent to and adapted to bind inwardly to-

ward said abutment, and manually operated means adapted to simultaneously retract said dogs.

5. In a holding device of the class described, a casing provided with clearance openings through its edges, a middle bearing abutment, a pivotally mounted locking dog at each side of and adapted to bind inwardly toward said abutment, and a manually shifted member, having link connections with each of said dogs for simultaneously retracting the same.

6. In a holding device of the class described, a casing, a middle bearing abutment, a pivotally mounted locking dog at each side of and adapted to bind inwardly toward said abutment, a disk rotatably mounted on a stud on said abutment and links pivotally connected to said disk in said dogs, said disk and said links co-operating to retract said dogs.

7. A holding device comprising a casing provided with clearance openings through its edges, a centrally spaced abutment, a stud on said abutment, a pivotally mounted spring pressed locking dog at each side of and adapted to bind inwardly toward said abutment, a disk having spaced abutments thereon, rotatably mounted on said stud, and links pivotally connected with said disk and said dogs, said abutments on said disk being adapted to be engaged by a key to rotate said disk and simultaneously retract said dogs.

In testimony whereof I hereunto affix my signature.

WILLIAM A. RICHARDSON.
